Fredrik Johnson
ATTORNEY

UNITED STATES PATENT OFFICE

ALBERT HANRATTY, OF COLLINSVILLE, ILLINOIS

GRAINING COMB OR BRUSH

Application filed March 31, 1930. Serial No. 440,600.

My invention relates to graining combs or brushes for graining wood, metal or other surfaces by inexperienced persons as well as by those skilled in the art of graining surfaces.

The object of my invention is the provision of a graining comb embodying a pair of graining combs applied to a holder in predetermined relation so that one of the combs will be a lead comb and the other a follow up or straight graining comb.

A further object of my invention is the provision of a graining comb or brush which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1 is a top plan view of my graining comb as standing in normal position upon a surface to be grained.

Fig. 2 is a front elevation of the device.

Fig. 3 is an end view thereof looking in direction of the arrow in Fig. 1.

Fig. 4 is a top plan view of the device not assuming its normal position upon a surface to be grained.

In carrying out the aim of my invention, I employ a holder, or block A made of wood, or any other suitable material and which is provided, preferably, although not necessarily with a flat lower face 1 and a flat upper face 2, or in other words, the block shall be of even thickness up and down. The block is further provided with a flat rear face 3, a flat inclined front face 4 which lies at an angle of approximately thirty degrees relative to the rear face 3. The block is also provided with an end face 5 which inclines toward the rear face 3 and which face 5 is preferably provided with a little finger grip

impression or recess 6. It will thus be seen that the block is approximately V-shaped in top plan view, as shown in Fig. 4.

A suitable metallic graining comb B has its back 7 secured near its upper edge to the rear face 3 of the block A by means of suitable fastening devices, such as screws 8 or their equivalent, so that when the teeth 9 of the comb have been worn too much for further use, the comb can be removed and a new comb applied to the block. The teeth 9 of the comb extend downwardly a suitable distance below the lower face of the block and they are resiliently flexible so that they will yield when downward pulling pressure is applied to the device. The lower edges 10 of the teeth of the comb lie parallel with the lower face of the block A, and the side edges thereof lie parallel with the front and rear edges of the block A.

A suitable metallic graining comb C has its back 11 secured near its upper edge to the inclined or slanting front face 4 of the block A by means of suitable fastening devices, such for instance as screws 12, or their equivalent, so that when the teeth 13 of this comb become worn too badly for further use, the comb can be removed and a new front comb applied to the block A. The teeth 13 of the front comb C extend downwardly a suitable distance below the lower face of the block A and they are resiliently flexible so that they will also yield rearwardly when downward pulling pressure is applied to the device in pulling it over a surface to be grained, such a surface being shown in full and dotted lines in Fig. 1 and designated D.

From Fig. 2 of the drawings, it will be observed that the lower edges 14 of the front comb teeth 13 are inclined upwardly toward the wide end face 5 of the block A, so that the graining edges 14 of the teeth 13 progressively come nearer the lower face of the block A. It will also be observed that the teeth 14 which extend the greatest distance beyond the lower face of the block A, as shown in Figs. 2 and 3, do not extend the same distance from the lower face of the block that the teeth 9 do, but fall short of that distance.

This arrangement enables the operator to

place the combing device upon a surface to be grained in a slanting position, as shown in Fig. 3, so that the comb will set upon the surface to be grained in a position to allow 5 the comb to be pulled straight over the surface to be grained, or in a waving side motion, as desired.

From Fig. 2 of the drawings, it will be observed that the teeth 13 of comb C are disposed at an angle to the teeth 9 of comb B so that they cross the same at a predetermined angle, thus the teeth of the lead or front comb B are pulled over the surface to be grained with one end thereof in advance 15 of the other end thereof, whereas the teeth of the rear or follow up comb C do not have one end thereof in advance of the other end, excepting when the device is moved in one direction or the other, such for instance, as 20 when pulling the combs over the surface to be grained in a zig-zag or wavy side motion. In a straight pull of the combs over a surface to be grained, one side edge of the teeth 9 of comb B do not assume a position in advance 25 of the other side edge thereof, as will be apparent from Fig. 3.

The exact graining effect to be attained cannot be predetermined either in a straight pull of the device or in a zig-zag or waving 30 side pull of the device, but in either instance, a very attractive imitation oak graining effect is attained, even by the most unskilled person, as it requires no skill in graining by 35 the person using the graining combs to produce the most satisfactory results by merely pulling the device over the surface to be grained. Heart shapes and knots will appear even in a straight graining stroke of the 40 device, but greater variation in the graining effect is secured if a slight side waving motion is applied to the device when pulling it over the surface to be grained. However, a 45 perfect graining effect is attained by the inexperienced person as well as the person who is skilled in graining surfaces, as the grain produced cannot be predetermined, this being known by having used the same stroke upon the same surface, and, in the second instance the grain would show up different 50 than it did in the first instance. However, in each instance the graining produced was perfect by a single stroke from one end of a painted surface to be grained to the other end thereof, thus it obviates the necessity of going 55 over one graining operation with another operation to produce a satisfactory graining effect and by the use of a single tool without necessarily having to change its position upon the surface being grained.

60 The many advantages of the herein described invention will readily suggest themselves to those skilled in the art to which it appertains.

From the foregoing description, it is evident 65 that a simple device for this purpose

has been disclosed, but it is to be understood that I do not desire to restrict, or limit myself to the very details of the construction shown and described, which is merely illustrative, it being obvious that changes, not 70 involving the exercise of invention, may be made without conflicting or departing from the spirit of the invention within the scope of the appended claims.

What I claim is:

1. In a graining device, the combination with a holder, of a pair of metallic combs having resilient teeth, the teeth of the comb applied to the rear face of the holder having their graining edges disposed in a plane substantially parallel with the upper face of the holder and the teeth of the comb applied to the front face of the holder having their graining edges at an angle to the graining edges of the teeth of the first mentioned comb. 80

2. In a graining device, a holder, a metallic graining comb having its back attached to the rear face of said holder with the graining edges of all the comb teeth disposed an equal distance below the lower surface of 90 the holder so as to be in a plane parallel with the lower face of the holder and a metallic graining comb having its back attached to the front face of the holder with the graining edges of all the comb teeth disposed in an 95 inclined plane from one end of the comb to the other end thereof.

3. In a painted surface graining device, a lead comb, a follower comb, a holder for said combs, the lead comb being disposed at 100 an angle to the follower comb and the teeth of the lead comb crossing the teeth of the follower comb at a suitable angle.

4. In a painted surface graining device, a lead comb, a follower comb, a holder for 105 said combs, the lead comb being disposed at an angle to the follower comb, the teeth of the lead comb crossing the teeth of the follower comb at a suitable angle and said holder having a finger receiving recess 110 formed in one of the side faces thereof.

5. In a graining device, a holder, a lead graining comb attached to said holder and a follower graining comb attached to the holder, the teeth of the lead comb being disposed to cross the teeth of the follower comb at a suitable angle thereto. 115

6. In a graining device, a holder, a lead graining comb attached to said holder and a follower graining comb attached to the 120 holder, the graining edges of the teeth of the lead comb being disposed in an inclined plane relative to the plane of the graining edges of the teeth of the follower comb.

7. In a graining device, a wedge shaped 125 holder in plan view, a follower graining comb attached to the rear face of said holder and a lead graining comb attached to the front face of said holder and the graining edges of the lead comb being disposed in an 130

inclined plane relative to the plane of the
graining edges of the follower comb.

8. In a graining device, a holder, a lead
graining comb attached to said holder and a
follower graining comb attached to the holder,
said combs being disposed in relation to
each other in such a manner that the device
will lean toward the user when positioned
upon a painted surface to be grained.

10 In testimony whereof, I have hereunto
affixed my signature.

ALBERT HANRATTY.
